UNITED STATES PATENT OFFICE.

HARRY F. KUMLER AND INGEMAR K. RYSTEDT, OF DAYTON, OHIO, ASSIGNORS TO THE MODERN COMB AND DEVICE COMPANY, OF DAYTON, OHIO, A CORPORATION OF OHIO.

DESIGN FOR A SHELL FOR A SPARK-PLUG.

55,133.

Specification for Design.

Patented May 11, 1920.

Application filed February 12, 1919. Serial No. 276,672. Term of patent 7 years.

To all whom it may concern:

Be it known that we, HARRY F. KUMLER, a citizen of the United States, and INGEMAR K. RYSTEDT, a subject of the King of Sweden, both residing at Dayton, in the county of Montgomery, in the State of Ohio, have invented a new, original, and ornamental Design for Shells for Spark-Plugs, of which the following is a specification, reference being had to the accompanying drawing, forming part thereof.

Figure 1 is a side elevation of the assembled spark plug embodying the shell form-

ing the subject matter hereof. Fig. 2 is a top plan view thereof.

I claim:

The ornamental design for a shell for a spark plug as shown.

In testimony whereof, we have hereunto set our hands this 8th day of February, A. D. 1919.

HARRY F. KUMLER.
INGEMAR K. RYSTEDT.
